UNITED STATES PATENT OFFICE.

JAMES H. GRAVELL, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

ELECTRIC SWITCH.

1,200,485.

Specification of Letters Patent. Patented Oct. 10, 1916.

Application filed June 17, 1914. Serial No. 845,522.

To all whom it may concern:

Be it known that I, JAMES H. GRAVELL, a citizen of the United States, residing at Philadelphia, in the county of Philadelphia and State of Pennsylvania, have invented certain new and useful Improvements in Electric Switches, of which the following is a specification.

My invention relates to electric switches, particularly such as are adapted to be used in connection with electric welding machines.

The object of the invention is to provide a switch of simple and cheap construction, large current carrying characteristics, and so mechanically arranged that all wearing parts may easily and quickly be replaced.

Other objects of my invention relate to the provision of means for overcoming defects in switch construction and the provision of novel constructions and combinations of parts as will more fully appear hereafter.

The switches now on the market for electric welding machines, with which I am familiar, are chiefly adapted for efficient use with currents of less than 100 amperes. When large currents are carried, such for example, as those above 100 amperes, the electric contacts are quickly consumed and the switch becomes excessively heated, causing any spring mechanism employed to lose its temper, and ruining the insulating materials used, thereby disabling the whole switch. Another objectionable feature of most of the switches now on the market is that the same are not inclosed and are therefore very hard on the eyes of the operator because of the constant flashing, and are also liable to cause fire if any light combustible material happens to be near the flashing contacts.

Another very serious defect with the usual electric welding switch with which I am familiar is that known as "sticking," that is, the contacts under some conditions weld fast together, preventing the switch from breaking the circuit at the proper instant because of which the materials being welded by the machine may be spoiled. By my invention, these objections are overcome and a switch is provided of cheap, simple and

rigid construction, which may be used to advantage both on light and heavy currents with no danger or annoyance from the arcing of the contacts and with no possibility of the latter sticking.

Among the features of my improved switch it may briefly be stated that provision is made for moving the movable element of the switch into contact to make the circuit, under the actuation of a spring which is operated by the operating lever or hand member of the switch, the movement of the movable element of the switch in the opposite direction, to break the circuit, being caused directly by the actuation of the operating lever itself, aided by a strong spring. More broadly, this feature of my invention may be described as the provision of mechanism whereby a certain amount of pressure is applied at the point of contact of the switch elements when the circuit is made, and a greater amount of pressure, such as to prevent the sticking of the contacts, is applied at the point of contact when the circuit is to be broken.

Other features of my invention comprise adjustable terminals extending within an inclosing casing, and a member within the casing movable toward and away from the terminals with a substantially straight line motion parallel to the axes of the terminals and carrying a contact plate so mounted thereon as to equalize the pressure between the same and the switch terminals when contact is made therewith.

In order that a clearer understanding of my invention may be had, attention is hereby directed to the accompanying drawings forming part of this application and illustrating a preferred embodiment of my invention.

In the drawings, Figure 1 represents a vertical cross-section through a switch construction embodying my invention, Fig. 2 is a horizontal section taken on line 2—2 of Fig. 1, and Figs. 3 and 4 are cross-sections taken respectively on lines 3—3 and 4—4 of Fig. 1.

Referring to the drawings, the casing 1 preferably consists of a metal box formed of stamped steel having flanges at the upper edges thereof for securing thereto the top

- 2 formed of fiber or other suitable insulating material. When the fiber top 2 is attached to casing 1 by bolts 3 or other suitable securing means, the construction constitutes a box open at both ends as shown in Fig. 1. The two electrodes or terminals of the switch, 4 and 5 extend inwardly through two holes provided therefor in the fiber top 2. The electrodes are firmly held in proper position by castings 6 and 7, preferably of brass which are secured to the top 2. The terminals 4 and 5 are readily lowered into the casing, as they wear away, by adjusting the same by means of the set screws 8, which extend through the holders 6 and 7 and press against the electrodes. The connecting wires may be attached to suitable lugs upon the holders 6 and 7.
- The lower contact of the switch comprises a copper bar 9 which is mounted within the casing for movement toward and away from the terminals 4 and 5, this contact bar 9 being preferably so mounted as stated as to cause the pressure between the same and the switch terminals to be equalized when the bar is brought in contact therewith. In the preferred form of my invention, this is accomplished by mounting bar 9 for a limited rocking movement about a pin 10. This pivot pin 10 extends through a hole in the center of contact bar 9 and is mounted in the two prongs of a fork 11 which are secured upon either side of an upright member 12 formed of fiber or other insulating material, fork 11 being secured to the fiber upright by suitable means such as bolts 13. The copper bar 9 is so mounted between the arms of the fork 11 as to permit the same to swing through a small angle from the horizontal before the same comes in contact with the upper edge of the upright 12 at either side of the pivot pin 10.
- Upright 12 with its pressure equalizing contact plate 9 is moved in a substantially vertical plane as stated toward and away from terminals 4 and 5 in the operation of the switch. Also, as stated, I provide means for breaking the contact between bar 9 and the switch terminals under a pressure sufficient to prevent sticking of the contacts, while the mechanism for bringing the contacts together to make the circuit need not cause the exerting of so much pressure at the point of contact between plate 9 and the switch terminals. The preferred means for obtaining these results will now be described.
- The operating lever 15, of the switch, preferably comprising parallel side portions as shown, is preferably provided with a handle 16 and is pivoted upon a rod 17 mounted in the sides of the casing 1. A lever or link 18 is pivotally mounted at one end upon the same rod 17 and at its other end upon a rod 19, which latter extends through the fiber upright 12. The operating lever 15 extends for some distance beyond its pivot in the direction of upright 12 as shown, this end of lever 15 normally resting upon a strap 20 formed integral with or secured to link 18 which latter preferably comprises parallel portions located at both sides of upright 12 as shown.
- A lever 21 is mounted on rod 22, which is supported in holes formed in the opposite side walls of casing 1, lever 21 comprising two parallel portions extending on both sides of upright 12 in the same manner as link 18, lever 21 being secured to the upright 12 by means of a pin 23 extending through the upright. Lever 21 is parallel to link 18, rods 19 and 23 and 17 and 22 forming the corners of a parallelogram. The side portions of lever 21 are joined at their rear end by a portion 24 to which is secured preferably by electric welding a cross bar 25 provided at each end with notches for the attachment of springs 26. The lower ends of springs 26 are attached to lugs at the ends of a strap 27 secured to and extending across operating lever 15 as shown. A compression spring 28 is interposed between the bottom of the casing 1 and the operating lever 15, the upper end of this spring being attached to the central portion of strap 27, the springs 26 being attached to the ends of strap 27. Spring 28 is considerably stronger than springs 26. The operation of the switch will be clear from the above description. The switch is shown in the drawings in its "off" position in which it is maintained by spring 28. When the switch is to be operated to connect terminals 4 and 5, operating lever 15 is depressed, spring 28 being compressed and standard 12 being raised until the copper bar 9 contacts the lower end of electrodes 4 and 5. This movement of standard 12 and bar 9 is effected by means of springs 26 which are extended by the depression of the operating lever and by the oscillation of lever 21 about its pivot caused by the pull thereon of springs 26. The movement of standard 12 is approximately in a straight vertical line because of the fact that link 18 and the lever arm 22, 23 of lever 21 connected to the standard are parallel and of the same length. When contact is made between bar 9 and the terminals 4 and 5, the movements of the bar and of the other movable parts of the switch cease with the exception of the movement of the operating lever 15 which may be continued until the operating lever comes in contact with the floor of the switch box. This continuation of the movement of the operating lever after all the other working parts of the switch have stopped causes the extremities of the operating lever to leave the strap 20 on lever 18, the springs 26 to

be further extended and spring 28 to be further compressed. The pressure exerted by bar 9 upon terminals 4 and 5, it will thus be seen, is entirely independent of the pressure exerted on the operating lever and is wholly governed by the strength of the springs 26. When the operating lever 15 is released, it is forced upwardly by spring 28 and springs 26, lever 15 swinging about its pivot 17 until the inner ends of lever 15 engage strap 20 on link 18, when the upwardly directed force of spring 28 causes the direct actuation downwardly of the upright 12 and bar 9, the downward movement of the inner end of lever 15 being transmitted directly and positively to the upright 12 through the engagement of lever 15 with the strap 20 on link 18. This movement is continued until standard 12 comes in contact with the floor of the switch box 1. It should be noted that springs 26 are made strong enough only to insure good contact between bar 9 and the terminals 4 and 5, whereas spring 28 is made strong enough to exert a considerable force so as to always insure the breaking of the contact between bar 9 and the switch terminals even if the bar and the terminals should become "stuck" or welded together.

It should be noted that the rocking movement of bar 9 as described enables the latter to equalize its pressure between the terminals 4 and 5 and that the parallel motion given the fiber upright 12 causes a good square contact between the terminals and bar 9. The operating means described permits a greater pressure to be applied to bar 9 at the point of contact of the same with the switch terminals when breaking the contact therewith than is applied to bar 9 when contact is made with the terminals, the force applied at the point of contact in making the connection being no more than is necessary, in accordance with the strength of springs 26 and the force which may be applied to bar 9 in breaking the contact being positively and directly applied by means of the operating lever and being unlimited in amount so as to insure the breaking of the contact under all circumstances. The adjustment of the switch contacts should also be noted. Bar 9 may easily be removed and replaced by simply removing pivot pin 10. This provision may be of value since there is considerable wear on bar 9 because of the sparking of the contacts. The terminals 4 and 5 may be easily removed as they wear away by adjusting them in their respective holders 6 and 7 by means of the set screws 8.

It should be understood that my invention is not limited strictly to the details of construction illustrated and particularly described, but that the same is as broad in its scope as is indicated by the appended claims.

Having described my invention, what I

claim as new therein and desire to secure by Letters Patent of the United States is:

1. In an electric switch, the combination of switch terminals, means for connecting the same electrically, means for moving said connecting means into operative position, comprising an operating member and a spring, and means positively connected to said connecting means, position to be moved by said operating member, upon the opposite movement of the latter, for the positive actuation into inoperative position of said connecting means by said operating means upon breaking the electrical connection, substantially as set forth. 70

2. In an electric switch, the combination of switch terminals, a movable member for connecting the same, an operating lever, connections between said member and lever, effective upon actuation of said lever in one direction, for moving said member into connecting position, and comprising a spring, and connections between said lever and member, effective upon actuation of said lever in the other direction, for moving 90 said member out of connecting position, substantially as set forth. 80

3. In an electric switch, the combination of switch terminals, a movable member for connecting the same, an operating lever, 95 connections between said member and lever, effective upon actuation of said lever in one direction, for moving said member into connecting position, and connections between said lever and member, effective only upon 100 actuation of said lever in the other direction, for positively moving said member out of connecting position, substantially as set forth. 105

4. In an electric switch, the combination of stationary means, a member movable into and out of contact therewith, said means and member being arranged to close and open an electric circuit when in and out of contact respectively, and means for moving 110 said movable member into and out of contact with said stationary means, so arranged that a greater force is exerted on said movable member at the point of contact of said member and means upon the breaking of 115 such contact, than upon the making of such contact, substantially as set forth. 120

5. In an electric switch, the combination of stationary means, a member movable into and out of contact therewith, said means and member being arranged to close and open an electric circuit when in and out of contact respectively, an operating member, connections between said operating member and movable member, effective to operate 125 the latter into contact with said stationary means upon movement of said operating member in one direction, and comprising a spring, and means positively engaged by said operating member upon movement 130

- thereof in another direction, for moving said movable member out of contact with said stationary means, substantially as set forth.
5. In an electric switch, the combination of stationary means, a member movable into and out of contact therewith, said means and member being arranged to close and open an electric circuit when in and out of contact respectively, an operating member, connections between said operating member and movable member, effective to operate the latter into contact with said stationary means upon movement of said operating member in one direction, and means for applying retracting pressure upon said movable member, only upon movement of said operating member in a different direction, adapted to cause greater force to be applied 20 to said movable member in withdrawing the same from contact with said stationary means than was exerted upon the same upon its movement into contact with said stationary means, substantially as set forth.
25. In an electric switch, the combination of stationary means, a member movable into and out of contact therewith, said means and member being arranged to close and open an electric circuit when in and out of contact respectively, an operating member, means for causing movement of said operating member in one direction to move said movable member into contact with said stationary means with no more than a predetermined pressure, and means intermediate 35 said operating and movable members for causing movement of said operating member in a different direction to move said movable member out of such contact with a pressure which may exceed such predetermined pressure, substantially as set forth.
30. In an electric switch, the combination of switch terminals, a member mounted for movement into and out of electrical connection therewith, a pivoted operating lever, a second lever parallel to the first, connected at one end to said member, and a spring connecting the free end of said second lever with a movable portion of said first lever, substantially as set forth.
35. In an electric switch, the combination of stationary and movable contact means, an operating lever, an operating connection between said lever and movable contact means comprising a lever and a spring connecting said levers, a link pivotally connected to said operating lever and movable contact means, and means for operatively connecting said link and said operating lever 40 when the latter moves in the direction required for breaking contact between said stationary and movable contact means, substantially as set forth.
45. In an electric switch, the combination of stationary and movable contact means, an operating lever, an operating connection between said lever and movable contact means comprising a lever pivotally connected to said movable contact means and a spring connecting said levers, adapted to be tensioned by movement of said operating lever in one direction to move said movable means into contacting position, and a connection between said operating lever and movable means, operative only upon movement of said operating lever in the opposite direction for moving said movable means out of contacting position, substantially as set forth.
50. In an electric switch, the combination of stationary and movable contact means, an operating lever, a member connected to said movable contact means, and so positioned as to be contacted by said lever on movement of the latter in one direction only, to move said movable means out of contacting position, and means for moving said movable means into contacting position on movement of said lever in the opposite direction, substantially as set forth.
55. In an electric switch, the combination of stationary means, a member movable into and out of contact therewith, said means and member being arranged to close and open an electric circuit when in and out of contact respectively, an operating member, a spring connected to said operating member and movable member, adapted to be extended by movement of said operating member in one direction, to cause contact between said movable member and stationary means, a stronger spring engaging the operating member and compressed by the operative movement of the latter, and means whereby the latter spring becomes effective to move said movable member out of contacting position when the operating member is released, substantially as set forth.
60. In an electric switch, the combination of a casing, adjustable terminals extending into the same, a movable non-conducting member within the casing, means for moving the same toward and away from the terminals, bearing members carried by said movable member, a pin carried by said bearing members, and a contact plate pivoted on said pin, and adapted to swing through a small angle thereon, said plate extending normally at right angles to the axes of said terminals, and adapted to be brought into contact therewith, substantially as set forth.
65. In an electric switch, the combination of a pair of parallel adjustable terminals, an insulating member, a contact plate carried thereby and adapted to be brought into and removed from contact with said terminals, parallel levers pivotally connected at one

end of each of the same to said insulating member, and arranged to form a parallel motion device, and means for operating one of said levers to move said member in a substantially straight line movement toward and away from said terminals, substantially as set forth.

This specification signed and witnessed this 15th day of June, 1914.

Correction in Letters Patent No. 1,200,485.

It is hereby certified that in Letters Patent No. 1,200,485, granted October 10, 1916, upon the application of James H. Gravell, of Philadelphia, Pennsylvania, for an improvement in "Electric Switches," an error appears in the printed specification requiring correction as follows: Page 3, line 74, claim 1, for the word "position" read *positioned*; and that the said Letters Patent should be read with this correction therein that the same may conform to the record of the case in the Patent Office.

Signed and sealed this 9th day of January, A. D., 1917.

[SEAL.]

F. W. H. CLAY,

Acting Commissioner of Patents.
